UNITED STATES PATENT OFFICE.

GEORG HAERTEL, OF BERLIN, GERMANY.

ARTIFICIAL ARM AND HAND.

1,322,108.

Specification of Letters Patent. Patented Nov. 18, 1919.

Application filed March 10, 1916. Serial No. 83,376.

To all whom it may concern:

Be it known that I, GEORG HAERTEL, residing at Berlin, Germany, have invented certain new and useful Improvements in and 5 Relating to Artificial Arms and Hands, of which the following is a specification.

This invention relates to improvements in artificial hands, the object of the invention being to provide means for moving the 10 thumb of an artificial hand, and comprising a sleeve or sleeves secured to the stump of an amputated arm and carrying a plate with inclined surfaces which has a rod arranged in its center which is journaled in 15 the base of the artificial arm and serves to guide the sleeve and the stump of the forearm, while the inclined surfaces upon rotation of the stump act upon said endwise movable rod and the rod engages cams provided at the movable part of the artificial hand.

With the above and other objects in view, the invention consists in the construction, combination and arrangement of devices 25 hereinafter described and claimed.

In the accompanying drawings—

Figure 1 is an elevation showing the general arrangement of the artificial hands, the parts of which are to be moved by the raising and lowering of the stump of the forearm.

Fig. 2 is a sectional view of said hand, on a larger scale.

In accordance with my invention, the artificial hand 1, is connected by means of pivotally arranged levers or bars 2 to sleeves 3 which are firmly clamped around the ends of the upper arm and forearm adjacent to the elbow, in such manner that the artificial hand 1 is not affected by the rotation of the 35 stump 4 of the forearm. At the end of the stump 4 a sleeve 5 is fixed, said sleeve having a cross section corresponding to the stump 4 and having a plate 6 provided at its free end, said plate having two oppositely arranged inclined surfaces 7 and 8 which are parallel with each other and which 40 coöperate respectively with rods 9 and 10, which rods are movable lengthwise in openings in the base 20 of the artificial hand.

The ends of said rods are provided with rollers 14 and 15, the rollers 14 bearing against the inclined surfaces 7 and 8, and the rollers 15 against the cam surfaces 11 45 and 12 of the movable parts of the artificial

hand (in the example shown, the movable thumb 13) respectively. In the center of the plate 6 carrying the inclined surfaces, a pin 16 is fixed, which rotates in a bearing provided in the base 20 of the artificial hand 60 and which is adapted to guide the plate as well as the stump of the arm.

The operation of the device is as follows:

In the normal position of the stump of the arm, the movable part (thumb 13) is in its 65 middle position. The rollers 14, 15 of the rods 9 and 10 always bear against the surfaces 7, 8 and 11, 12 respectively. If the stump of the arm is rotated in a direction in which the hands of a watch travel, the 70 rod 10 is moved forward and pressing against the surface 12 separates the thumb 13 from the fingers of the artificial hand. At the same time the rod 9 is moved backward by the inclined surface 11 and the 75 roller 14 of said rod is freely sliding along the inclined surface 7. If the stump of the arm is rotated in a direction opposite to the direction of travel of the hands of a watch, the rod 9 is moved forward to close the 80 thumb 13 and finger 1 and simultaneously the rod 10 is moved backward by the surface 12 without doing work.

It may be noted that said device may also be used if the arm has been amputated above 85 the elbow-joint, in which case the rotations of the stump of the upper arm may be used to move the parts. In such case the displacement of the rods arranged in the sleeve of the upper arm would be transmitted to 90 the hand by suitable means such as for instance Bowden-wires.

If desired, the inclined surfaces 7, 8 may be resiliently connected to the plate 6, so as to obtain a gentle pressing together of 95 the single parts and to prevent the device from being damaged.

To increase the number of movements of the parts the above mentioned device for utilizing the movements of the shoulder blade to move the parts of an artificial hand by means of a cable wire or the like may of course be employed in combination with the last described device.

What I claim is:

1. In artificial limbs of the character described, in combination, a plate freely projecting into said limb, inclined surfaces at one end of said plate, rods endwise movable in the base of said limb adapted to be 110

acted upon by said inclined surfaces and to engage the movable parts of the limb and means at the other ends of said rods for receiving the stump of the arm.

- 5 2. In a device of the character described for moving the fingers of artificial arms, in combination, oppositely inclined surfaces on a plate freely projecting into said artificial limbs and at one end of said plate, rods end-
10 wise movable in the base of said limb adapted to be acted upon by said inclined surfaces, cams upon the movable parts of said limbs, adapted to be engaged by said rods, and a sleeve at the other end of said plate surrounding the stump of the arm, said inclined surfaces at the plate upon rotation of the stump of the arm moving said rods for the purpose of moving the fingers and thumb of same.
- 15 3. In artificial limbs of the character described, in combination, a sleeve surrounding the stump of an arm, a plate on said sleeve, oppositely inclined surfaces on said plate, a rod journaled in the base of the limb and
- 20

adapted to be moved endwise and to be engaged by said inclined surfaces upon the rotation of the stump, and cams provided at the movable parts of the artificial limb adapted to be engaged by said rods. 25

4. In an artificial limb of the character described in combination, a sleeve surrounding the stump of the arm a plate carried by said sleeve provided with inclined, resilient surfaces, a rod journaled in the base of the artificial limb and secured in the center of 30 said plate and adapted to guide the sleeve and the stump, said inclined surfaces upon the rotation of the stump acting upon said endwise movable rods and cams provided at the movable parts of the artificial limb 35 40 adapted to be engaged by said rods.

In testimony whereof I affix my signature in presence of two witnesses.

GEORG HAERTEL.
